UNITED STATES PATENT OFFICE.

MORRIS L. GOLDSTEIN, OF PROVIDENCE, RHODE ISLAND.

DESIGN FOR A CHARM OR PENDANT.

59,211.

Specification for Design.

Patented Oct. 4, 1921.

Application filed February 4, 1921. Serial No. 442,553. Term of patent 14 years.

To all whom it may concern:

Be it known that I, MORRIS L. GOLDSTEIN, a citizen of the United States, residing at Providence, in the county of Providence, State of Rhode Island, have invented a new, original, and ornamental Design for a Charm or Pendant, of which the following is a specification, reference being had to the accompanying drawing, forming a part

Figure 1 is a front elevation of my new charm or pendant.

Fig. 2, a sectional view of the same taken on the line 2—2 of Fig. 1.

I claim:—

The ornamental design for a charm or pendant, as shown.

MORRIS L. GOLDSTEIN.
